UNITED STATES PATENT OFFICE.

FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

DRILL-PRESS.

1,167,887.

Specification of Letters Patent. Patented Jan. 11, 1916.

Application filed June 14, 1915. Serial No. 34,046.

REISSUED

To all whom it may concern:

Be it known that I, FREDERICK F. CLARKE, citizen of the United States, residing at Franklin, in the county of Venango and 5 State of Pennsylvania, have invented certain new and useful Improvements in Drill-Presses, of which the following is a specification.

The object, construction and utility of this 10 invention are herein set forth with sufficient clearness to enable those skilled in the art of machine-tool construction to make and use the same, and the scope of my invention is clearly defined in the claims.

15 As heretofore constructed, drill presses of the spindle type here shown have been provided with gearing for driving the drill spindle, whereby a large number of changes of speed of said spindle are obtainable, and 20 in fact, it has been the aim of the manufacturers of such drill presses to provide in their machines, all the possible changes of speed which might be required in all the various aggregate lines of work for which 25 the machines might be used. The reason for this provision lies in the fact that, in the commercial manufacture of such machine tools, it can seldom be known in advance, for what line of work they will be used.

30 While these many changes of speed appear to be requisite in order to enable the manufacturers of the drill presses to meet various requirements, it is often the case that the user of the machine will require only a few 35 of these possible speeds. This means that, wherever such drills are used in the manufacture of duplicate or interchangeable parts,—upon a single detail of which the drill may be continuously employed or op- 40 erated for a long period of time—the greater number of the possible speed changes of the spindle are never used, and that the gearing whereby said speed changes are obtainable is not only unnecessary, but, in ad- 45 dition thereto, the presence of same undesirably complicates the machine, adds to its power consumption, and adds to the cost of its upkeep and maintenance, to which may be properly added an unnecessarily 50 high first cost.

It is, therefore, the object of my invention, to provide a drill press of the spindle type, especially adapted for manufacturing purposes, and to supply the same with gear-

ing for revolvably driving the drill-spindle, 55 whereby the particular drill-speed requirement of each individual user may be met without the employment of superfluous gearing and unnecessary speeds, and wherein the objectionable qualities above mentioned, incidental to the use of the usual type of gearing are obviated.

One form of construction whereby I attain said objects is clearly illustrated in the drawings, the various figures of which are 65 as follows:

Figure 1 is a side elevation of the upper portion of a drill press, which embodies my invention. Fig. 2 is a detail. Fig. 3 is a plan view of a train of gearing whereby my 70 inventive idea is clearly embodied, and represents approximately a section on line III—III of Fig. 1.

The construction shown is substantially as follows: The spindle of the drill press is 75 indicated by the reference numeral 1 in Figs. 1 and 3. Revolvble motion is transmitted to said spindle from a power-receiving pulley 2, through a train of gearing and suitable shafting, in which are included the 80 following elements: a revolvble shaft 3, upon which are rigidly mounted the spur gears 4 and 5; a revolvble shaft 6, arranged in suitable proximity to and parallel with said shaft 3; upon said shaft 6 are mounted 85 the longitudinally-shiftable gears 7 and 8 which are feathered to said shaft 6 by means of the gib or feather 9, so that said shaft 6 may be driven by either of said gears 7 or 8. Said gears may be shifted upon said shaft 90 6 so that gear 7 will mesh with gear 4, as shown in Fig. 3, or so that gear 8 will mesh with gear 5, as shown by the dotted lines in said Fig. 3, thus providing two changes of 95 transmissive speed from shaft 3 to shaft 6. Upon the outer end of shaft 6 is mounted a readily-removable gear 10, which meshes with and transmits motion through another readily-removable gear 11 to the shaft 12 which carries said gear 11. Said 100 gears 10 and 11 are adapted to be transposable or interchangeable, and, being of different diameters, are adapted to cause by such transposition, changes of speed in the transmission of motion from shaft 6 to shaft 105 12. The transmission from shaft 12 to spindle 1, is through the gears 13 and 14 to shaft 15, and gears 16 and 17; said gear

17 being feathered to and operably mounted upon said spindle 1 by means of the feather 18.

For the purpose of causing said gears 10 and 11 to be readily accessible, for removal and transposition, or for the substitution of other gears therefor, I inclose the same in a specially-provided case formed upon the side of the bed or column of the drill press and 10 provide said case with a swinging or otherwise readily-removable or opening cover 26, which, when closed, serves to retain said gears 10 and 11 upon their respective shafts by contact with the outer ends of the hubs 15 thereof, as shown in Fig. 3.

For the purpose of shifting the gears 7 and 8, as above stated, upon their shaft 6, I provide the following means: Mounted in the column of the drill press is a horizontally positioned, longitudinally-movable rod 21, which carries a gear engaging member 22, which engages the gear 8. Said rod 21 is provided with a rack 23 which is operably engaged by a pinion 24. Said pinion 24 is 25 carried by a hollow shaft 25 that is provided with a lever or handle 25' adapted for turning said shaft 25 and pinion 24 to operate rod 21 and shift the gears 7 and 8. A shaft 26 passes through shaft 25 and is 30 adapted to actuate the belt-shipper 27, which shifts the driving belt from the driving pulley 2 to a loose pulley that is mounted in proximity to said pulley 2. Inasmuch, however, as said elements 25, 26 and 27 do not 35 form a portion of the invention here set forth, a more detailed description of same will not be given.

From the foregoing description it will be readily understood that, with the gearing 40 here provided, four changes of speed are made possible, and that two gears of any desired ratio may be quickly and easily sub-

stituted for the gears 10 and 11, and that said gears 10 and 11, whatever their ratio may be, are readily transposable; that by 45 such transposition, two changes of speed are provided.

When the drill-speed requirements for any service are known, they may be readily cheaply and quickly supplied by providing 50 gears 10 and 11 of a suitable ratio. At a small expense for extra pairs of gears 10 and 11 of various ratios, other requirements may be met, through a large range of speed.

I claim the following:

1. The combination with the spindle of a drill press, of a train of gearing operable to revolve said spindle, two parallel shafts having fixed centers, two intermeshing gears in said train mounted upon said shafts, said 60 gears differing as to ratio or diameter and being transposably mounted for the purpose of causing, by the transposition thereof, a variation in the revoluble speed of said spindle.

2. The combination with the spindle of a drillpress, of a train of gearing operable to revolve said spindle and comprising among its elements two parallel shafts having fixed centers, a gear mounted upon each of said 70 shafts, said gears being in mesh with each other and being also interchangeable for the purpose of causing a change of speed between said shafts by such interchange, additional gears in said train shiftably mounted 75 upon their respective shafts whereby additional variations of speed are obtainable.

In testimony whereof I affix my signature in presence of two witnesses.

FREDERICK F. CLARKE.
